DESIGN FOR A SPECTACLE FRAME

Charles O. Cozzens, Southbridge, Mass., assignor
to American Optical Company, Southbridge,
Mass., a voluntary association of Massachu-
sets

Application February 24, 1939, Serial No. 83,175

Term of patent 14 years

To all whom it may concern:

Be it known that I, Charles O. Cozzens, a citizen of the United States of America, residing at Southbridge, in the county of Worcester and State of Massachusetts, have invented a new, original, and ornamental Design for a Spectacle Frame, of which the following is a specification, reference being made to the accompanying drawing, forming a part thereof.

Fig. I is a perspective view on an enlarged scale of a spectacle frame showing my new design;

Fig. II is a top plan view of the spectacle frame shown in Fig. I; and

Fig. III is a sectional view taken on line III—III of Fig. II and looking in the direction of the arrows.

The essential features of my design for a spectacle frame are shown in full lines, portions of the temples being omitted for convenience of illustration.

I claim:

The ornamental design for a spectacle frame, substantially as shown and described.

CHARLES O. COZZENS.
